(57) **CLAIM**

The ornamental design for a posture corrector, as shown and described.

DESCRIPTION

FIG. 1 is a perspective view of the posture corrector in accordance with the present invention;
FIG. 2 is a front elevation view thereof;
FIG. 3 is a rear elevation view thereof;
FIG. 4 is a top plan view thereof;
FIG. 5 is a bottom plan view thereof;
FIG. 6 is a left side elevation view thereof; and,
FIG. 7 is a right side elevation view thereof.

1 Claim, 7 Drawing Sheets
